United States Patent [19] Stone

[11] Patent Number: Des. 278,624

[45] Date of Patent: ** Apr. 30, 1985

[54] ELECTRICAL POWER MODULE

[75] Inventor: Davis P. Stone, Canyon Country, Calif.

[73] Assignee: Hopkins Engineering Company, Calif.

[**] Term: 14 Years

[21] Appl. No.: 509,216

[22] Filed: Jun. 29, 1983

[52] U.S. Cl. D13/24; D13/11; D13/35

[58] Field of Search ..... D13/11, 12, 13, 24, D13/30, 35; 361/331, 332, 333, 334, 347, 346, 349, 357, 358, 380, 390; 174/52 R, 50

[57] CLAIM

The ornamental design for an electrical power module, as shown and described.

DESCRIPTION

FIG. 1 is a front perspective view of an electrical power module showing my new design;

FIG. 2 is a rear perspective view thereof;

FIGS. 3 and 4 are respectively front and rear elevational views thereof on a reduced scale;

FIGS. 5 and 6 are respectively left and right elevational views thereof on a reduced scale; and

FIGS. 7 and 8 are respectively top and bottom plan views thereof on a reduced scale.

Fig.1.
